UNITED STATES PATENT OFFICE.

HELEN V. NORDGREN, OF GILLETTE, WYOMING.

CORSET.

Application filed June 23, 1921. Serial No. 479,862.

To all whom it may concern:

Be it known that I, HELEN V. NORDGREN, a citizen of the United States, residing near Gillette, in the county of Campbell and State 5 of Wyoming, have invented certain new and useful Improvements in Corsets, of which the following is a specification.

This invention relates to corsets and more particularly to those of the type known as 10 front lace corsets.

The object of this invention is to provide a corset of this character so constructed that ready access to the sanitary napkin may be had at any time and the corset held snugly 15 fitted at the lower portion thereof and present a smooth unobstructed appearance there being no protuberances such as would render the wearing of a single skirt impossible.

Another object is to provide a garment of 20 this character with means for holding the stays or bones against longitudinal movement.

With these and other objects in view the invention consists in certain novel features 25 of construction as hereinafter shown and described and then specifically pointed out in the claims, and in the drawings illustrative of the preferred embodiment of the invention.

30 In the accompanying drawings:—

Figure 1 represents a front elevation slightly in perspective of the corset constituting this invention shown applied.

Fig. 2 is a rear elevation thereof.

35 Fig. 3 is an enlarged rear elevation of the corset showing the flap in open position.

Fig. 4 is a detail transverse section taken on the line 4—4 of Fig. 2, and

40 Fig. 5 is a similar view taken on the line 5—5 of Fig. 2.

In the embodiment illustrated a corset 1 is shown having stay receiving casings 2, the stays or bones 14 being held securely within this casing by means of eyelets 3 which prevent all possibility of the bones moving longitudinally in the casing and working out through the tops or bottoms as frequently occurs with those not so held. Any desired number of these eyelets may be used, 45 preferably being used throughout the length of the stays.

This corset 1 is provided at the center back portion thereof at its lower edge with a longitudinally extending slit 4 finished in 50 any suitable manner and having an elastic pinning member or strap 5 secured to the

inner face of the corset at the inner end of the slit as is shown clearly in Fig. 3.

A cover flap 6 is fixedly secured at one side edge to the lower portion of the corset 60 as shown at 7 and is adapted to overlie the slit 4 in the corset when in closed position and be held in such position by snap fasteners shown at 8, said fasteners being preferably celluloid covered, although not necessarily so.

An elastic fabric section 9 is carried by the lower portion of the flap 6 and is designed to permit the corset to yield around its lower edge to insure the comfort of the 70 wearer when bending or stooping or otherwise moving. The snap fasteners 8 are arranged across the corset at a point above the slit 4 therein and down one side at a point spaced from the slit so that when the flap 6 75 is closed and snapped into position it will present a smooth appearance as shown in Fig. 2 and will completely conceal the slit and yet ready access thereto may be provided by simply disengaging the fasteners 80 in the manner well understood.

A flap 10 is also employed in the front of the corset being fixedly secured adjacent one front edge thereof as shown at 11 and detachably connected at its other side edge to 85 the other front edge of the corset by snap fasteners indicated at 12 and which are preferably celluloid covered to prevent any possibility of rusting or injury to the garments of the wearer incident to the use of metal 90 fasteners of this character.

An elastic pinning strap 13 is carried by the flap 10 preferably secured at one end to the lower end thereof as is shown in Fig. 1, and cooperates with the trap 5 at the rear 95 of the corset to support a sanitary napkin in the well known manner.

From the above description it will be obvious that a corset constructed as herein described and shown will present a smooth 100 neat appearance when the flaps are in closed position as shown in Figs. 1 and 2, and yet these flaps may be readily opened when found desirable to do so.

The bone retaining eyes or eyelets shown 105 at 3 extend through the casing 2 and the body portion of the corset 1 also through the bone shown at 14 and the ends of these eyelets are upset as shown in Fig. 4 to prevent their accidental detachment and they operate to securely hold the stays or bones 14 110 against longitudinal movement in their cas-

ings 2; thus avoiding objectionable working through at their upper and lower ends in the casings of these bones which often causes much discomfort to the wearer of the cor-
5 set in addition to puncturing the other garments.

The preferred embodiment of the invention is disclosed in the drawings and set forth in the specification, but it will be understood that any modifications within the scope of the claimed invention may be made in the construction without departing from the principle of the invention or sacrificing any of its advantages.

15 15 What is claimed is:—

1. A corset of front lace type comprising a body member having its lower portion centrally of its back provided with a slit opening at the bottom edge of said body member, 20 a pin strap secured to the inner face of said body member above and underlying said slit, a bendable closure flap having one side edge thereof secured to said body member adjacent to one side of the slit and formed with 25 an elastic lower portion, said flap adapted to extend over and conceal said slit and said body member and flap having associated means for connecting the other side thereof and its top to the body member above and 30 at the other side of the slit.

2. A corset of front lace type comprising a body member having its lower portion centrally of its back provided with a slit opening at the bottom edge of said body member, 35 a pin strap secured to the inner face of said body member above and underlying said slit, a bendable closure flap having one side edge therof secured to said body member adjacent to one side of the slit and formed with an elastic lower portion, said flap adapted to extend over and conceal said slit and said body member and flap having associated means for connecting the other side thereof and its top to the body member above and 40 at the other side of the slit, and a bendable front flap having one end secured to the lower portion of one end of said body member at the front thereof and said front flap having its free end and said body member provided with associated means for connecting the said free end to the other end of the body member, whereby said flap will extend across the opening between the ends of said body member at the front thereof, and 45 a pinning strap depending from said front flap.

50 In testimony whereof, I affix my signature hereto.

HELEN V. NORDGREN.
